*J. B. Westwick,
Mangle.*

No. 96646.

Patented. Nov. 9. 1869

United States Patent Office.

JAMES B. WESTWICK, OF GALENA, ILLINOIS.

Letters Patent No. 96,646, dated November 9, 1869.

IMPROVED MANGLE.

The Schedule referred to in these Letters Patent and making part of the same.

To all whom it may concern:

Be it known that I, JAMES B. WESTWICK, of Galena, in the county of Jo Daviess, and State of Illinois, have invented a new and improved Mangle; and I do hereby declare that the following is a full, clear, and exact description thereof, which will enable others skilled in the art to make and use the same, reference being had to the accompanying drawings, forming part of this specification.

This invention relates to new and useful improvements in mangles; and consists of improved arrangements of devices for working a table reciprocatingly under a pressing and smoothing-roller, on which table the clothes to be mangled are spread, the pressing and mangling-roller being provided with adjustable weights, for varying the pressure.

Figure 1 represents a side elevation of my improved machine, and

Figure 2 represents an end view, with some parts sectioned.

Similar letters of reference indicate corresponding parts.

A A are two side frames, preferably made of cast-metal, and connected together by rods B.

C C are two rollers, mounted in bearings at each end, in the said side frames.

They support the reciprocating table D, having two straight-toothed racks E on its lower side.

F is the upper mangling-roller.

It is provided with bearings G, arranged to move up and down in slots in the housings, and they are connected to levers H, jointed to the frame at I, and connected, by rods K, to other levers L, pivoted to the frame at M, and provided with weights N, for varying the pressure of the roller on the clothes, the said weights being adjustable along the said levers.

The table and roller are, in practice, covered with cloth, and the cloth cover for the table is connected to one end by a clamp, and at the other by a roller, having a ratchet and holding-pawl, for stretching the cloth over the table.

The rods K are made in two parts, and are connected by a screw-threaded sleeve, K', in which the rods may be adjusted for shortening or lengthening them. In practice, I propose to provide them with

right and left-hand threads, so as to effect the adjustments by turning the sleeves.

O is a driving-shaft, carrying toothed wheels P, gearing with the racks E, for moving the table back and forth.

For simple and cheap machines, this shaft may have a hand-crank for turning it back and forth; but for the best class of machines, to be operated by hand, or other power, constantly moving in one direction, I provide a curved rack, Q, on the face of a disk, R, connected to the said shaft, which rack is toothed on both the outer and inner faces, and over the ends, with which I gear a driving-pinion, S, mounted on a shaft, T, fixed in a bearing, U, capable of sliding up and down in a slotted plate, V, supported in bolts W, projecting from the main frame.

Between the ends of the curved rack, a guide-plate, X, is attached to the disk, having two curved guiding-faces, Y Z, which come against the inner end of the shaft T, at each time one end of the said toothed rack arrives at the pinion, by which the pinion is carried either up or down, as the case may be, around the end of the said rack, to reverse the motion thereof, and thereby that of the table.

The table is provided with guide-pulleys a, suitably arranged in the frame, to work against the edges of the table, for controlling its position laterally.

Having thus described my invention,

I claim as new, and desire to secure by Letters Patent—

1. The combination of the table D, rollers C, driving-shaft O, wheels P, racks E, pressing and mangling-roller F, sliding bearing G, levers H L, connecting-rods K, and weights N, when all arranged substantially as specified.

2. The combination, with the driving-shafts O and T, of the disk R, toothed rack Q, guide X, pinion S, and sliding bearing U, all substantially as specified.

3. The combination, with the frame A, and the subject-matter of the second claim, of the slotted plate V, supported on the bolts W, substantially as specified.

Witnesses: JAMES B. WESTWICK.

W. A. DU BOIS,
CHARLES FLICK.
